WEDGE BAR

Henry Herbert Toogood, Los Angeles, Calif.

Application June 10, 1930. Serial No. 460,257

6 Claims. (Cl. 25—131)

This invention relates to wedge bars and has relation more particularly to a device of this kind especially designed and adapted for use in connection with ties employed with concrete forms, and it is an object of the invention to provide a bar which minimizes the use of the ties in comparison with the number now generally employed, thus permitting the building of concrete forms with economical advantage to contractors or the like in rural localities who are now generally handicapped by reason of the expense incurred in the rental and transportation of the supporting elements to be used with the ties.

Another object of the invention is to provide a wedge bar which will afford economy in the production of a wall as it will permit without sacrifice of safety the omitting of a large number of ties now generally used to hold and bind the two sides of a wall form together.

It is now the general custom in many localities to build the sides of the forms of boards of narrow widths and to use a tie between each joint of these boards to prevent the boards from bending outwardly when the form is being filled with concrete. By reducing the number of ties required my improved wedge bar materially reduces the expense incident to producing a concrete wall.

The constructor of forms for concrete walls when they are "built in position" of individual boards has a choice of two methods of holding the sides of the form or containing element together, one method is to use a tie between each and every board at the proper longitudinal distance one from the other with the tie having a pin or the like to hold the boards in position, and the other method is to use a tie of such tensile strength that a tie need be used only in every alternate joint between boards or even between every third or fourth joint with the ends of the ties designed with loops or holes so that a steel rod can be used as a continuous supporting element. The first method is costly not alone by reason of the large number of ties required but on account of the high labor charge necessary to handle so many separate pieces, both in erecting and dismantling the forms. The second method, while economical as to both material and labor, is limited to use in those centers of population where the question of transportation of the required steel rods can be readily overcome. My improved wedge bar permits the use of either of the two methods with a tie placed between each and every joint whether the ties be in close juxtaposition vertically one above the other or whether they be placed in a staggered formation, either with or without the continuous

supporting elements or rods or other anchoring means now in use.

The invention consists in the details of construction and in the combination and arrangement of the several parts of my improved wedge bar whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in elevation of a wedge bar constructed in accordance with an embodiment of my invention and in applied position;

Figure 2 is a view in side elevation of the device as shown in Figure 1 with the adjacent form boards in section;

Figure 3 is a sectional view taken substantially on the line 3—3 of Figure 2;

Figure 4 is a sectional view illustrating an embodiment of my invention wherein a wedge bar is comprised as a part of a built up lumber stud;

Figure 5 is a view in front elevation of a wedge bar constructed in accordance with a further embodiment of my invention unapplied but with the tie loop in engagement therewith;

Figure 6 is a view in side elevation of the bar as illustrated in Figure 5 in applied position, the associated form boards being in section;

Figure 7 is a sectional view taken substantially on the line 7—7 of Figure 6;

Figure 8 is a view partly in section and partly in plan illustrating a still further embodiment of my invention in applied position;

Figure 9 is a fragmentary view in front elevation illustrating an additional embodiment of my invention;

Figure 10 is a fragmentary view in side elevation of the structure illustrated in Figure 9;

Figure 11 is a sectional view taken substantially on the line 11—11 of Figure 9;

Figure 12 is a fragmentary view in front elevation illustrating an embodiment of my invention for use in connection with a sheet metal tie;

Figure 13 is a sectional view taken substantially on the line 13—13 of Figure 12.

In the embodiment of my invention as illustrated in Figures 1, 2 and 3, the bar B is of a T-construction. As illustrated in Figure 1, the bar B adjacent each end thereof is provided in its

65

110

head flange 1 and at opposite sides of the web flange 2 with longitudinally disposed slots 3. These slots 3 are immediately adjacent to the web flange 2 and similar ends of the slots 3 communicate with an opening 4 provided in the head flange 1 and which opening is not intersected by the web flange 2 as particularly illustrated in Figures 1 and 2.

The portions of the web flange 2 at the same 10 sides of the openings 4 have their outer longitudinal margins inclined downwardly, as at 5, toward the openings 4 whereby wedge members W are provided. Each of the openings 4 is of a size to permit the ready insertion therethrough of the 15 end loop 6 of a form tie of a type now well known in use so that as the bar is moved lengthwise in the required direction, a wedge member W comprised in the bar structure will be received within the loop 6 as illustrated in the accompanying 20 drawings.

The bar B is provided with a multiple of wedges and while only two are illustrated in the accompanying drawings it is to be understood that additional wedge members may be constructed as 25 the requirements of practice may necessitate and dependent particularly upon the length of the bar.

In practice the bar B is positioned against the 30 outer faces of the form boards F and, as illustrated in Figures 1 and 2, the bar B is of such a length as to have effective coaction with a plurality of superimposed boards, thus minimizing the number of ties needed in comparison with the number now generally used. By imposing 35 requisite impact upon an end of the bar B the wedge members W will have effective entry or passage through the loops 6 of the ties resulting in an effective assembly and maintenance of a form. When it is desired to remove a bar B a suitable implement is engaged within an opening 7 provided in an end portion thereof and, as 40 illustrated in Figure 2, in the web flange 2.

A bar B may be employed in connection with only a single side of a form and it is further intended that the bar be used in connection with ties that are arranged in staggered relation. It 45 is also possible to use my improved bar with two or more form clamps now well known to the trade.

I do not wish to be understood as limiting myself to having the bar B of T-formation as the bar B' illustrated in Figure 5 may constitute an angle iron with one of the flanges 8 formed to provide the desired wedge member W', and with the second flange 9 of the bar B' to one side of but immediately adjacent to the flange 8 provided with 55 the slots 3', each of which coacting with an opening 4'.

If desired the bar B'' may constitute channel iron as illustrated in Figure 8, wherein the flange 8' is formed in substantially the same fashion as the flange 8 while the base flange 9' is provided with the desired slots and openings.

In Figure 4 of the drawings I illustrate an embodiment of my invention wherein a bar B is mounted and secured in a lumber frame L and which in such assembly serves not only as a multiple wedge bar but also as a supporting bar. This lumber frame is preferably built up of boards of prevailing size. This lumber frame is of essential advantage as it permits the requisite studs for a form to be built up at an operation, thus avoiding excessive cost of studs proper plus the transportation cost.

I have found in practice that with the use of 75 bars constructed in accordance with an embodiment

of my invention, it is possible to eliminate one-half and often two-thirds of the number of ties previously required in the building of a form. It is also to be stated that the bars should be made of different weights, the heavier bars to be used at the bottom of forms and said bars decreasing in weight as they are used at higher altitudes.

I have also found that it is entirely practical to construct a wedge bar by welding short pieces of angle iron to a steel bar and then shaping the projecting flange of the angle iron as desired. This particular structure with a slight modification can be employed with equal facility and advantage in connection with wire ties or sheet metal ties.

The embodiment of my invention as illustrated in Figures 9 to 11 inclusive is intended for use in connection with wire ties. In these figures a steel bar 10 has riveted, welded or otherwise securely anchored thereto the outer marginal portion of a flange 11 of a short length of angle strip 12. The second flange 14 of the strip 12 has its outer or free longitudinal marginal portion formed to provide a wedge 15. An end portion of the flange 11 immediately adjacent the flange 14 and extending along the lower portion of the wedge 15 is provided with an open slot 16 whereby the end loop 17 of a wire tie may be readily engaged with the flange 14 for requisite coaction with the wedge 15.

While I am only illustrating a single strip 12, it is to be understood that as many of these strips may be attached to the bar 10 as desired. I also find that it is of advantage to use for the bars 10 discarded sucker rods, such as used in connection with oil wells.

In the embodiment of my invention as illustrated in Figures 12 and 13 the flange 11' of the strip 12' is riveted or otherwise anchored to an offset portion 18 provided in the bar 10' and the slot 16' is of such width to permit the wedge 15' of the plate 14' to be effectively employed in connection with a sheet metal tie.

From the foregoing description it is thought to be obvious that a wedge bar constructed in accordance with my invention is particularly well adapted for use by reason of the convenience and facility with which it may be assembled and employed, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. As a new article of manufacture, a form tie bar having an elongated longitudinally extending opening therethrough, and a wedge member disposed at right angles to the bar and having a portion overlying said opening, said member having an extension formed therewith and constituting a brace.

2. As a new article of manufacture, a form tie bar having an elongated longitudinally extending opening therethrough, said opening extending laterally through one marginal edge of the bar, and a wedge member disposed at right angles to the bar and having a portion overlying said opening, said member having an extension formed therewith and constituting a brace to prevent bending of the bar.

3. As a new article of manufacture, a flat form tie bar having a plurality of elongated longitudi-

nally extending openings therethrough disposed intermediate the marginal edges of the bar, and wedge members disposed at right angles to the bar and having a portion overlying each opening, one of said members having an extension formed therewith and constituting a brace.

4. As a new article of manufacture, an elongated form tie bar having a plurality of offset portions, wedge members disposed within said offset portions and extending in the direction of the length of the bar, and means for securing the wedge members in substantial alinement with the longitudinal axis of the bar and within said offset portions.

5. The combination with a tie having a termi-

nal hook, of a tie clamp including a body having a hook receiving slot, the walls of said slot constituting means for confining the hook and preventing it from spreading open, and a non-removable wedging element constantly seated in the body and adjustably engaging the confined hook.

6. A tie clamp including a body for sliding engagement with a form, said body having a slot for receiving the hooked end of a tie and holding it from spreading, and a wedge integral with the body and extending longitudinally within the slot from one end thereof for entering and adjustably engaging said hooked end.
